BURGLAR ALARM

Filed Dec. 23, 1921

John Marshall
INVENTOR
BY George C. Coffey
ATTORNEY

UNITED STATES PATENT OFFICE.

JOHN MANUEL, OF BUFFALO, NEW YORK.

BURGLAR ALARM.

Application filed December 23, 1921. Serial No. 524,362.

To all whom it may concern:

Be it known that I, JOHN MANUEL, a citizen of the United States, residing in Buffalo, in the county of Erie and State of New York, have invented new and useful Improvements in Burglar Alarms, of which the following is a specification.

This invention relates to a burglar alarm and more particularly to an alarm which is adapted to be operated by relatively movable parts of a building, such as the sash of a window which is moved relatively to the frame and which is designed to give a combined explosive, ringing and lighting alarm so that if one or the other of these alarms should fail to operate, the remaining alarms will still operate to scare away a burglar.

It is the object of this invention to provide an alarm of this character which is comparatively simple and inexpensive in construction, which can be readily applied to various movable parts of a building so that the same will be operated to give an alarm when such part is moved and which can be readily loaded for use, as well as disconnected and rendered inoperative when not required.

In the accompanying drawings:

Figure 1 is a fragmentary perspective view of my improved burglar alarm applied to the sash and frame of a window.

Figure 2 is a top plan view of the alarm showing the manner of connecting the same with a signal bell and signal lamps.

Figure 3 is a vertical longitudinal section of the cartridge firing portion of the alarm and associated parts.

Similar characters of reference refer to like parts throughout the several views.

Although this burglar alarm may be applied to various parts of a building which move relatively to each other, the same is shown in the present instance, applied to a window having a frame 10 and a sash 11 movable vertically in this frame.

The preferred organization of my improved alarm comprises an enclosing casing 12 which may be secured to the window frame in any suitable manner so that the same is stationary. At one end of this casing the same is provided with an upright barrel 13, the upper end of which is constructed to form a perforated seat 14 while its lower end is opened. Into this seat a cartridge 15 is adapted to be passed downwardly so that the rim 16 of the cartridge

rests on top of the seat. Upon firing this cartridge by striking the top of the same, the charge in the body thereof will be delivered downwardly through the barrel 13 and escape at the lower end thereof, thereby giving a detonating sound which will serve as an alarm to arouse the occupants of the building and persons nearby that some unauthorized person is attempting to enter the building. The firing of this cartridge is effected by means of a hammer 18 which projects upwardly through a slot 19 in the upper part of the casing and is pivoted with its lower part within the casing by means of a pin 20 so that the hammer swings in a vertical plane. At its outer end the hammer is provided with a firing pin or needle 21, which is adapted to hit the top of the cartridge and is provided in rear of said firing place with a finger piece 22 whereby the hammer may be drawn backwardly and cocked. The hammer is held in its cocked position by means of a sear 23 which is pivoted on the inner side of the casing and adapted to be engaged with one or another of two notches in the lower part of the hammer according to whether you wish to cock the hammer half-way or full. This sear is yieldingly held in its operative position by means of a sear spring 26 which is interposed between the rear side of the trigger 27 projecting downwardly from the sear and an abutment 28 which bears against a bracket 29 and the adjacent part of the casing, this spring being guided and held in its operative position by means of a rod 30 which passes through the spring 26 and through openings in the bracket 29 and the trigger 27 and has the abutment secured thereto. The sear is released from the hammer by means of a pull line 31 passing through a slot 32 in the lower part of the casing and connected with the trigger 27. Upon pulling downwardly on the line 31, the sear is released from the hammer and when this occurs the hammer is thrown forwardly by means of a spring 33 preferably of C-form arranged in the casing and bearing at one end against the bottom thereof while its upper end bears against a shoulder 34 formed on the rear part of the hammer. When the hammer is thus released by the sear, its firing pin or needle hits the cartridge and explodes the same, thereby giving an alarm and scaring away thieves and others who may be attempting to enter the

building by opening the window. The downward motion or pulling effect upon the trigger for sounding the alarm is preferably transmitted to the same from the 5 window sash 11 by providing the free end of the pull line 31 with a link 35 which engages with a hook 36 on the window sash and passes the intermediate part of the pull line around a guide pulley or roller 37 on 10 the adjacent part of the window frame. By this construction an upward motion of the sash 11 will cause a downward pull upon the trigger 27 and an explosion of the cartridge by the hammer.

15 In order to confine the cartridge securely in place and prevent the same from becoming dislodged during the explosion, the keeper 38 is provided which engages over the top or upper end of the cartridge and is 20 provided with a central opening 39 through which the firing pin or needle 21 can be passed in order to reach the upper end of the cartridge and fire the same. This keeper is movably mounted on the upper part of 25 the barrel 13 so that the same can be moved into and out of its operative position, for which purpose the keeper is pivoted by means of a pin 40 on one side of its opening 39 on the top of the barrel 13. On one side 30 of its pivot, this keeper is provided with a handle or finger piece 41 whereby the same can be conveniently manipulated and moved into and out of its working position. While in its operative position that part of the 35 keeper opposite to its pivot pin 40 engages underneath a hook-shaped retainer 42 which projects upwardly and inwardly from the adjacent part of the casing. This keeper is swung to one side of the cartridge seat when 40 a cartridge is applied to a seat or removed therefrom, but when this keeper is swung over the cartridge, which is arranged on this seat and engages underneath the retainer hook or lip 42, the cartridge will be securely 45 held in place and prevented from rising and instead will be compelled to discharge its contents through the lower end of the barrel.

50 In addition to giving an explosion alarm, this cartridge discharging mechanism is preferably combined with an electrical device whereby an electrically operated alarm may be given at the same time that the explosion alarm is given. In the preferred 55 organization this electrical alarm an electric bell 43 and one or more electric lamps 44 are utilized, which are connected parallel with a battery 45 and two terminal contacts 46, 47 which are mounted on an insulated 60 support 48 which forms the top of the enclosing casing 12, in such position that these

contacts 47 are arranged at opposite sides of the hammer 18 and are adapted to be engaged by contact pins 49 projecting from opposite sides of the hammer. The latter, as 65 well as the contact pins 49, are made of metal so that when the hammer is released for discharging the cartridge the pins 49 will simultaneously engage with the contacts 46 and 47 and thus close the electric circuit 70 containing the bell and the electric lights and thus not only fire the cartridge but also ring the bell and light up the vicinity of the premises wherever the lamps are located. The contacts 46 and 47 are preferably 75 constructed of spring metal so that they are held under the downward pressure of the contact pins 49 and thus not interfere with the firing of the cartridge.

By thus combining the cartridge exploding mechanism with the electrical signaling device greater certainty in scaring away thieves or burglars is assured, inasmuch as the electric warning signal and the explosion alarm are not likely to be inoperative at 80 the same time and thus provide means for giving either an explosion alarm or an electric alarm and in most instances both of these alarms, when an unauthorized entrance into the building through the window is attempted.

This alarm is comparatively simple in construction and can be readily applied to any relatively movable members of building structure by persons without any particular skill, and when installed the same ensures giving either an explosion alarm or an explosion alarm and an electrical alarm depending upon the manner in which the same is installed and operated.

100 I claim as my invention:

A burglar alarm adapted to be interposed between two relatively movable members of a building comprising a casing adapted to be mounted on one of said window members, a barrel arranged on said casing and having a seat adapted to receive a cartridge, a hammer pivoted on the casing and having a firing pin adapted to strike the cartridge, a spring adapted to move the hammer forwardly, a sear adapted to hold said hammer in its retracted or cocked position and provided with a trigger, a bracket mounted on the casing, a guide rod passing through said bracket and trigger and having a collar or abutment engaging said bracket, a spring surrounding said guide rod and interposed between said abutment and trigger, and a connection between said trigger and the other window member.

105 110 115 JOHN MANUEL.
